UNITED STATES PATENT OFFICE.

RALPH JOSEPH PROVENÇAL, OF ST. JOHNSBURY, VERMONT.

ENVELOP.

1,192,558.

Specification of Letters Patent. Patented July 25, 1916.

Application filed April 4, 1916. Serial No. 38,830.

To all whom it may concern:

Be it known that I, RALPH J. PROVENÇAL, a citizen of the United States, residing at St. Johnsbury, in the county of Caledonia and State of Vermont, have invented certain new and useful Improvements in Envelops; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in safety envelopes and it has for its object to provide an envelop of this character which, when properly folded and sealed, will make it impossible for an unauthorized person to tamper with the contents of said envelop without mutilation of the same which would be immediately detected.

The invention consists in the arrangement of parts, all as will be more fully herein-after described, shown in the accompanying drawings and then specifically defined in the appended claim.

My invention is illustrated in the accompanying drawings, in which:—

Figure 1 is a plan view of a blank in unfolded position. Fig. 2 is a view of the envelop folded and sealed. Fig. 3 is a section on line 3—3 of Fig. 2, and Fig. 4 is a cross section taken on line 4—4 of Fig. 2.

Reference now being had to the details of the drawings by letter, A designates a sheet of paper or other suitable material, which is so cut as to form end flaps A' and A², a bottom flap A³ and a top flap A⁴. The end flaps are provided with slots A⁵, and the bottom flap has similar slots A⁶, all of which are adapted to register when the end flaps are folded in, and the bottom flap is folded upon said end flaps. The bottom flap A³ has a flange B which is provided with openings or pockets B' which contain a melt-

able material, as indicated by C, and said flange B is adapted to be folded over on the inside of the end flaps A' and A², thus forming the envelop body. The top flap A⁴ is 50 provided with long strips of locking tongues A⁷ which are adapted to be folded back along the dotted lines A⁸, and said tongues have openings D which, when the tongues are folded back, will form pockets which 55 are filled with a meltable material D'. After the matter to be contained in the envelop has been placed therein, the tongues A⁷ are inserted through the alining slots A⁵—A⁶ and A⁸ of the end and bottom flaps, and are 60 bent upward and folded flat so as to bring the meltable material D' into contact with the meltable material C carried by the flap B.

It will thus be seen that, by passing a heated iron over the front of the envelop, 65 the meltable materials B' and C will be fused together, thereby providing an envelop which will have to be destroyed in order to remove the contents thereof.

What I claim to be new is:—

An envelop comprising a sheet which has wings adapted to be folded over one another to form bottom and end closures, said wings having slots formed in alinement and adapted, when folded, to register with one 75 another, a bottom wing having a flap provided with pockets with meltable material therein, a portion of the blank having a flap provided with tongues spaced apart and projecting therefrom and having openings 80 therein which, when the tongues are folded, are adapted to form pockets with a meltable material therein, said tongues adapted to engage the registering slots, and openings and pockets filled with said meltable material 85 being adapted to contact one with another.

In testimony whereof I hereunto affix my signature in presence of two witnesses.

RALPH JOSEPH PROVENÇAL.
